Patented Apr. 29, 1919.

UNITED STATES PATENT OFFICE.

EDWIN S. HOPKINS, JR., OF NEW YORK, N. Y.

MODIFIED VIVIGRAPHIC RECORD AND PROCESS.

1,302,367.

Specification of Letters Patent. Patented Apr. 29, 1919.

Application filed March 2, 1909, Serial No. 480,952. Renewed July 31, 1918. Serial No. 247,671.

To all whom it may concern:

Be it known that I, EDWIN S. HOPKINS, Jr., a citizen of the United States, residing at New York, in the county of New York

5 and State of New York, have invented a certain new and useful Improvement in Modified Vivigraphic Records and Processes, of which the following is a specification.

10 My invention relates chiefly to the synchronization of cinematographs, kinetoscopes, cameragraphs, biographs, mutoscopes and various machines of the nature for producing effects of motion; hereinafter usually termed motion picture machines; with graphophones, phonographs, talking machines and other means of such general character for reproducing sound, hereinafter usually referred to as sound reproducing 15 machines, and the synchronization or simultaneous reproduction of their effects and of corresponding visible and audible effects.

The principles of my invention are as follows:

20 I produce a film; and in the words film and motion picture film and cinematograph film I herein include all other means of producing effects of motion of successive photographs, however arranged, as on separate 25 leaves, cards, and on disks and in other ways; causing the figures of the film when being photographed to give forth the desired sounds in the proper sequence, so that the visible effects will be true to nature.

30 A sound record of a general phonographic character, of the sounds which it is desired to have accompany the film is then procured in any convenient manner. The record may be made first and the film photographed 35 while the actors follow the sounds as a guide for their gestures, and this is the method most often employed.

40 Whichever is taken first, a certain amount of care should be exercised so that when the 45 film is projected at a normal speed and the sound record advanced at a normal speed simultaneously from a common initial moment they will approximately coincide. Since however, the record and film are not 50 made simultaneously, certain deviations will

exist even where the greatest degree of care and skill is used, and such deviations will destroy the effect of synchronism unless overcome.

In my invention I produce a modified 55 copy of the record, as more fully hereinafter described, which by reason of the modifications enables synchronism to be effected.

When a record exists which approximately corresponds with a film, and which when 60 the record and film are simultaneously advanced at normal speeds will produce approximate effects of synchronization, it is apparent that the reason why an exact synchronization is not obtained when the machines 65 are advanced at a fixed ratio of speed is that the cogent parts of the record are not distributed along the phonic section or line in the same relative positions as are distributed the corresponding visible effects along the 70 length of the film. The redistribution of the cogent parts of the phonic section, by inserting blank or silent spaces at some points and by eliminating spaces at other points will suffice to effect the necessary re- 75 distribution. To effect this on a wax-like record is a matter of great difficulty and for practical purposes impossible, though it may readily be effected on a tape record by cutting out bodily parts of the record and in-

serting at certain points other parts, a plan 80 which also may be employed in the case of a single phonic line on the periphery of a wheel or disk of large diameter. In order to redistribute the cogent parts of the phonic 85 section of a wax like record, either a disk or preferably a cylinder, I resort to another plan, a highly useful one within my invention, which consists largely of making a modified copy of the master by the process 90 of engraving a blank from a master record by causing the cutting stylus of the blank to be guided by the reproducing stylus of the master, and during such operation stop- 95 ping one of the machines and advancing the other, or drawing it back any desired distance thus introducing changes in groove length, and consequently in the proportion- ate distribution of the cogent parts along the groove, such additions or eliminations 100

of parts of the phonic section of the duplicate as compared with the master being preferably made at silent or non-cogent parts of the records. Such a modified copy of a record I shall hereinafter usually refer to as a filmetted record.

Having explained the fundamental principles of my invention, and certain desirable objects to be attained thereby, before proceeding with a detailed description of the means employed, I will mention certain other objects, which though not necessarily involved, are often desirable to be attained:

It is generally desirable in procuring the filmetted record that no deviation in the groove from a true helix exist.

It is generally desirable that the exact amount of space to be accounted for in the phonic section be known, and its location whether of insertion or omission known.

In carrying out my invention I find it generally desirable to employ the following apparatus and construction, but it is to be understood that less than all of the means herein described may for some uses be employed, or parts only may be employed, or other means similar may be substituted, and while the preferred forms embodying my invention are shown, many structural details may be varied, and many changes in details resorted to, and such other modifications be made as come within the appended claims, without departing from the scope and spirit of my invention, nor do I limit myself to the particular devices and processes shown and constructions indicated, although I believe them especially suited to the ends to be attained by my invention.

In the accompanying drawings forming a part hereof, and in which the same reference letters and numerals indicate the same or corresponding parts:

Figures 1, 2 and 3 show a form of recording and duplicating apparatus which I will usually hereinafter term a filmetting duplicator, the main purpose of which is to accomplish the distribution of cogent parts of phonic sections on the modified copy of a record at different proportional locations to those occupied by such cogent parts on the master; and in this term filmetting duplicator I include all apparatus which may be adapted to record and reproduce sound and sound records when used in this manner. The filmetting duplicator may not only be used for duplication of records but also by substitution of exchangeable parts for recording and reproduction. The term filmetting record also includes such forms of apparatus as advance the master record and the duplicated blank independently of each other.

Fig. 1 is a plan, Fig. 2 a side elevation

and Fig. 3 an end elevation of the filmetting duplicator. This machine is in many respects similar to forms of phonographic duplicators well known in the art, with certain new and useful additions. In duplicating records by such means, the master record is placed on its mandrel and the blank which is to be made a modified copy is placed on a nearby mandrel, both being revolved at the same speed. A ball pointed stylus is placed on the master so connected with a cutting stylus placed on the blank that the vibrations or movements of the ball pointed stylus in following the phonic section of the master are reproduced and engraved on the blank by the cutting stylus, the blank thus being for practical purposes an exact replica of the master record.

A useful procedure in my invention is to occasionally stop both records at some selected locations, preferably a blank space on the master, and holding one of them still, either the master or the blank, I move the other one a predetermined distance or angle, thus producing variations in the length of the phonic groove of one as compared with the other to the extent of the movement. Thus in reproduction no effect is noticed except that the spaces of silence between cogent parts are greater or less than before.

It will be seen that a form of apparatus could be constructed in which the records would remain stationary and the reproducing and engraving points would travel around them, but such a form would only be a modification within my invention, as would also be a form of phonograph in which the record would remain at rest and the engraving, or the reproducing point travel around it.

In the drawings, a master record 1 in Fig. 1 is shown in position on its mandrel 2, which revolves with spindle 3. A record blank 4 to be engraved, is in position on its mandrel 5, which revolves with spindle 6. Spindle 3 is tapered at the ends and is carried in centers 7 and 8, and spindle 6 is similarly tapered and carried in centers 9 and 10. Centers 8 and 10 are carried in gate 11, hinged at post 13, and closing against post 12. Side plate 14 has a bracket 15 to carry center 7 and an arm 16 to carry center 9. Pinion 17 affixed to spindle 6 meshes with gear 19 revolving on stud 20 and gear 19 revolving on stud 20 engages pinion 18 affixed to spindle 3. For some uses spindle 3 may be driven by the usual belt 22 over pulley 23. Posts 21 and 24 through which spindles 3 and 6 pass loosely, serve to support the mandrels when gate 11 is open, so that they will not fall out of position. As pinions 17 and 18 are of the same pitch, mandrels 2 and 5 revolve with equal velocities. Feed screw 25

is caused to revolve through gear 28 meshing with gear 26 revolving on stud 27 and driven by pinion 18, the feed screw being journaled at 29 in plate 14 and at 30 in post 31. The revolution of feed screw 25 causes feed apron 32 to move laterally when clamped thereto by screws 33-34.

Reproducer apron 35 slides on back rod 36, which is supported by post 37 and cross bar 38 which connects post 31 with post 39. Reproducer apron 35 is cut to admit feed apron 32, and carries reproducer ball stylus 40, shown best in Fig. 3, in holder 41. A different form of holder may be substituted, 15 adapted to carry an amplifying horn, or for some uses to carry an engraving stylus. The indentations in the phonic section of master record 1 being tracked by stylus 40, cause apron 35 to be bodily moved up and down 20 on back rod 36 as a pivot, the friction caused by the pressure of apron 32 against apron 35 in moving the apron 35 along laterally not being sufficient to prevent this vibration and the weight of apron 35 being such as to prevent any breaking down of the indentations 25 of the phonic section, and yet of sufficient weight as to cause the stylus to follow the indentations accurately. There is no fixed connection between the aprons, merely a contact at point 42. Recording apron 43 is similarly caused to be advanced by arm 44 of apron 35, there being no fixed connection between the aprons 35 and 43, but merely a contact at point 45. Apron 43 slides on rod 30 46 fixed in posts 47 and 39, similarly as apron 35 slides on rod 36. Apron 43 is free to move up and down on rod 46 as a pivot, and its weight is carried by the support of apron 35, the sunken surfaces 50 and 51 of apron 35 35 passing under arms 49 and 48 of apron 43, but not in mechanical connection therewith, the weight of apron 43 being thus supported ultimately on the stylus 40. Thus when stylus 40 enters a depression in the phonic 40 groove both aprons sink that much and when it passes over an apex they rise in unison. As aprons 35 and 43 are of equal lengths from their center of contact to rods 36 and 46, analogous portions on each will move 45 with equal amplitude, and thus cutting stylus 52 best seen in Fig. 2, carried by holder block 53 in apron 43, being disposed as far from the center of rod 46 as ball stylus 40 is from the center of rod 36, will cut indentations in the record blank corresponding to those in the master record, at the same time of course, cutting a helical groove in record 4 similar to that in record 1. Somewhat similar forms of duplicating machines 50 are in use in the art, acting on these principles. I make a novel and highly useful departure from the usual construction in a new form of mandrel or other means of changing the angular relation of the master and blank.

Under ordinary circumstances the master 65 and blank, when mounted on their mandrels are fixed with relation to each other, but I adopt a new form of mandrel in which the ends as 54-55 of mandrel 5 and 56-57 of mandrel 2 are affixed to spindles 6 and 3 70 respectively, while the center portions of the mandrels may be revolved at will with reference to the fixed ends, a certain amount of friction ordinarily holding the center parts firm in relation to the ends. Thus if end 55 75 be grasped between the thumb and fingers, the center portion 5 may be rotated about the spindle with the fingers of the other hand when some force is applied. A form of vernier scale dividing, in the illustrated 80 example, the mandrel and ends into twelve parts by division lines 58, provides a convenient means of determining the angle of revolution. Ordinarily one sixth of a revolution at a time is all that is required, 85 though any fractional part of a revolution or any number of revolutions may be made in either direction on either mandrel as desired.

When cutting stylus 52 in position on record 4 is ready for engraving the blank, and when it is desired to move record 4 through a movement of the mandrel 5 while master record 1 and mandrel 2 are at rest, it will be seen that as the aprons are at rest, the 90 resulting groove cut by stylus 52 when the blank is advanced will not be of a helical character, but will be merely circular in nature, which would in the course of a revolution cause the phonic line to overlap itself 100 and cease to advance. In order to impart the lateral advance necessary to cause stylus 52 to proceed helically with respect to the blank's surface when the feed screw and aprons are at rest, block 53 in which stylus 105 52 is mounted is carried on screw 59 journaled in lugs 60-61 on apron 43. The revolution of screw 59 will thus cause a lateral advance of cutting stylus 52 such as is necessary to describe the helical groove on record 4. 110

A partial cross section of this portion of the apparatus taken on line 62-63 is shown in Fig. 2, apron 43 and rod 46 being partially broken away to show it. As it is desirable for screw 59 not to be revolved while feed screw 25 is in action, and to be revolved only when the center part of mandrel 5 is being revolved while the remainder of the apparatus is at rest, and then 115 only in the same proportion, I provide gear 64 mounted near the inner end of mandrel 5. This gear 64 engages gear 65 which is affixed to the spindle 66 journaled in arm 16 and cross bar 38. These gears are constantly in operation when the rest of the machine is going but they alone move the screw when the other parts are at rest and 120

the center part of mandrel 5 is being moved, and being of the same size, one revolution of mandrel 5 will cause one revolution of spindle 66. Screw 59 is provided with a hole much larger than the diameter of spindle 66, so that ordinarily in operation the vibrations of apron 43 are not interfered with by spindle 66. In order to cause screw 59 to be revolved by spindle 66, when the remainder of the apparatus is at rest, and the center part of mandrel 5 is being moved, annular wedge 67 encircles rod 66 and is feathered to it so that the wedge and spindle revolve as one, the wedge being easily slideable along the spindle. When the mandrel 5 is ready to be turned, wedge 67 is forced into screw 59 so that the revolution of spindle 66 will thus cause the revolution of wedge 67 and screw 59, and thus as mandrel 5 is turned, gear 64 will move gear 65 and spindle 66 will thus cause the revolution of screw 59 which will give block 53 the lateral movement necessary to cause cutting stylus 52 to preserve the helical character of the groove. Block 53 moves in a well hole laterally in apron 43 between the lugs in which screw 59 revolves, but it is prevented by the sides of the well hole from having any but a lateral movement. Any number of revolutions of the mandrel may thus be made up to the limits of screw 59, and likewise the mandrel may be turned backward as the revolution of the screw 59 in the other direction will cause the cutting stylus to retreat in the helical groove without breaking it down. When the change in angle between the records has been accomplished, wedge 67 is disengaged and the whole apparatus may again be started, spindle 66 revolving but as an idle member, the lateral movement of stylus 52 then being derived from the feed screw 25.

A similar arrangement may be provided with reference to the ball pointed stylus, but as the corrections for synchronism will ordinarily be made on the blank, I have not shown the reproducer ball so adapted. Further a slight loosening of holder 41 if necessary will serve to accommodate such lateral movements as may be advisable, since the ball stylus already having its groove traced in the wax and bearing no cutting edges can thus be accommodated to a sufficient extent without special attachments such as are necessary in the case of the cutting stylus.

For some uses it is desirable not to operate the apparatus by the belt 22, which may then be disengaged, but by an electrical release through a train of gears operated by the same power that is applied to the belt.

Shaft 68, journaled in plate 14 is an extension of an inner shaft from the driving mechanism, from which belt 22 derives its

motion. Shaft 68 carries gear 69, with which it is in frictional connection by ring 70 of suitable frictional material. Gear 69 engages gear 71 revolving on stud 73, and gear 71 engages pinion 74 affixed to spindle 3 and of the same pitch and diameter as pinion 18. Consequently the rotation of shaft 68 will operate the whole apparatus. Affixed to gear 71 is a smaller gear 72, which engages gear 75 mounted on stud 77. Similarly mounted on stud 77 is pinion 76 which engages gear 80 mounted on stud 81. Gear 75 and pinion 76 are connected by spring 78, attached to both, which in the drawing is shown as a helical spring, but which may, if desirable be a spiral spring. Affixed to the hub of gear 80 is escapement wheel 79, detent arm 81 being provided with armature 83 and pivoted in bracket 82. Locking pallet 84 of detent arm 81 is held in position by spring 85, but whenever an electrical impulse is received by magnet 86, through terminals 87-88, armature 83 is attracted and one half a step is taken by wheel 79, the discontinuance of the impulse releasing the armature, and the pallet 89 being drawn down by the retraction of spring 85, the step is completed by wheel 79. When the apparatus is started, movement continues until the moment of the coiling of spring 78 prevents further progress, at which time impulses of electrical force delivered to the magnet will diminish the moment of the spring by permitting the revolution of gears 80 and 76, and thus the movement and speed of the whole apparatus will depend upon the frequency of the electrical impulses, shaft 68 being given a velocity such that it will be equivalent to or greater than the proportionate velocity of the escapement wheel. No retraction or backward movement will occur when the escapement wheel is stopped for shaft 68 continuing to revolve will wind spring 78 to a certain point and then will be permitted to continue to revolve through slipping of its frictional contact ring 70. Spring 78 further serves a useful purpose in diminishing the vibrations caused by the release of the escapement wheel. Other vibration absorbers may be inserted if advisable.

Magnet 86 is secured to lug 90 projecting from plate 14. When it is not desirable to have the apparatus controlled by the magnet and escapement, pinion 74 may be loosened from spindle 3, and moved out of engagement with gear 71, or 76 may be similarly moved out of engagement with 80.

A useful addition within my invention, to the phonograph or filmetting duplicator consists of a counting dial or other means of indicating the number of revolutions and the velocity of the apparatus. A convenient form is shown in the drawings. Pinion 17 bears on its side a bevel gear which engages

bevel gear 91 on spindle 95 journaled in lug 106 on arm 16 and in post 47, carrying bevel gear 92 which in turn meshes with bevel gear 93 on spindle 108 journaled in lug 105 5 on post 47, communicating motion to fingers 101 and 102 of dial 100 through bevel gear 104, spindle 96, bevel gears 106 and 98 and spindle 99, the journals of which are omitted from the drawing. Finger 101 is adapted to 10 indicate the number of revolutions of the mandrel 5 and finger 102 the parts of each revolution. For some uses a form of dial which shows the number of revolutions in integers on the periphery of dial wheels will 15 be useful.

Having now described certain of the mechanisms and manufactures employed, a more detailed explanation of how the objects of the invention are attained by the 20 means referred to is necessary.

Having procured a record which is approximately synchronous with the film to which it corresponds, trials are made in connection with the film to find the exact location 25 of the deviations. When their location is ascertained, the amount of variation in angular relation of master record and copy necessary to be corrected will at once be evident.

30 Thus, for example, it is evident that there are more words in the phonic section to that point than there are suitable actions on the film; therefore the words are occurring too soon and they must be moved along the 35 phonic section and the groove lengthened; the groove or phonic section being too short as compared with the film. This lengthening may be inserted at the given point, or parts of it may be inserted either between 40 subsequent, or preferably between preceding words.

On the other hand, if the words get behind, it is evident that the words are too widely separated, that is that the word that 45 should have been reached at such point is still farther along the phonic section. Thus more actions have taken place on the film than words therefor have been reached in the phonic section, and the groove must accordingly be shortened or spaces taken out of it to make the sounds more compactly placed, either at that point or farther on, but preferably prior thereto. A small portion 50 may be eliminated between each word if the most agreeable effect is to be secured.

In practice both the expedients mentioned will have to be undertaken in most instances, that is portions of the phonic section will have to be eliminated and other portions will 55 have to be lengthened, often alternately one and then the other.

It may be well to note that a difference of one sixteenth of a second between picture and sound is quite enough to impair the 60 effect of synchronism. A trotting horse will

in that length of time go almost three feet, and sound will travel slightly more than 68 feet. By observing a perfectly synchronized movement, as the impact of a ball, and then retreating to a point at which an interval 70 may be noticed between the sound and the moment of contact, the interval of time which will destroy synchronism can be ascertained with ease. The best effect is produced by having the sounds a trifle sharp, 75 that is premature, rather than the least particle flat, or delayed. A mathematically exact synchronism will of course be more or less flat to the audience, particularly to those in the rear of a large hall, while a considerable 80 degree of sharpness is more pleasing than the least flatness.

Having ascertained the locations and extent of the deviations between the film and record, the filmetting duplicator is then employed to produce a modified copy of a record in which such deviations are done away with.

The proper procedure is as follows: The master record bearing the deviations and the 90 blank are mounted on their respective mandrels, and the process of copying is carried on until the deviation is encountered. When the film gets ahead it is evident that the words which should be on the duplicated 95 record at that point are still farther along on the master. Two expedients can then be followed. The blank can be held and the master mandrel revolved the proper degree forward, or the master may be held and the 100 blank turned back. In the latter case, that part of the groove containing the last words will be scraped over and somewhat blurred by the cutting stylus when it advances again.

If it be undesirable to blur the sound or 105 to omit it, and if a highly exact effect is desired, the deviation may be divided between several portions of the previous phonic section, a little between each word, instead of it all being allowed for between two words, 110 using when necessary a fresh blank, a number of trial blanks often being used and discarded before a correct synchronic modified copy is obtained, or the master mandrel may be turned forward enough to account for 115 the deviation. In turning the mandrels the vernier scale 58 will be found useful and the screw 59 for causing the cutting stylus to follow a helical course should of course be put into proper connection before the duplicator is moved in either direction.

The master may be held at rest and the duplicating mandrel advanced, cutting a path in the wax free from indentations; or the copy blank mandrel may be held and the 125 master turned back.

If the copy be advanced, the path cut in the wax will have the effect of lengthening the interval between the words.

It is within my invention to modify the 130

filmetting duplicator so that it would not have to be stopped to make the changes indicated, the requisite alterations being made while the process of copying is going on.

5 The principles of my invention are readily applicable to all the various forms of sound reproducing machines as well as to those of the cylinder and disk type. In one form of phonograph, electrodeposition takes 10 place as a means of recording sounds. To apply my invention to such an instrument is only a matter of modification of detail, or adaptation. Similarly in the case of a phonograph which consists of a photographic 15 film bearing spaces of varying degrees of density caused by the effect on light of sound, and effecting reproduction by the projection of varying degrees of intensity of light through such film on a selenium cell 20 and transforming the varying effects back into sound through electrical means, a mere adaptation will suffice to suit my invention thereto, as will also be the case with the mere tape phonograph and the siren phonograph. 25

In this specification and claims, the expression, "sound reproducing machine" includes all forms of machines used for the production of sounds from records of 30 sounds once made or duplicates of records of sounds once made, as distinguished particularly from the kinds of machines which produce sounds from records which are not records of sounds once made, but which are 35 made independently of original sounds, though intended to produce sounds. Similarly, the expressions, "of a phonographic character" or "general phonographic character," include not only the sounds of the 40 instrument known as the phonograph, but also all other instruments reproducing sound from records of sound once made or duplicates thereof, irrespective of the sort of medium employed or the processes employed in securing the record, whether mechanical, chemical, photographic, electrical, or otherwise, and the expression "sound record" refers to all such records of a general 45 phonographic character as may be suitable 50 for use in reproduction of sounds in instruments or by processes of a phonographic character.

The expression "phonic section" refers to that part of a sound record which contains 55 the record, such as a groove on a cylinder, disk or tape, a band or space on a photographic tape or a chemical or physical line of any sort, while the expression "cogent part" refers to those parts of a phonic section 60 which have other than silent effects. The term "master" as applied to a record refers to the original record made, or a duplicate thereof which may be used for making modified copies.

65 The expression, "motion picture machine"

refers to any or all of the various forms of reproducing effects of motion by successive views, whether intermittently or regularly advanced, or whether arranged on films, cards, or otherwise.

70 What I claim is:

1. A modified copy of a phonographic record in which certain of the intervals between sound producing portions have been extended and certain ones contracted as 75 compared with the original from which it was produced, substantially as and for the purpose described.

2. A modified copy of a phonographic record, the phonic section of which is at certain parts elongated and at other parts contracted, as compared with the original, whereby to cause the several portions of the copied phonic section to bear such relation to the analogous portions of a motion picture film of the same matter, that synchronism of their effects will result when they are suitably advanced at a fixed ratio of speed, substantially as and for the purpose 85 described.

3. A modified copy of a phonographic record, the phonic section of which is elongated at certain locations as compared with the original, whereby to cause the various portions of the copied phonic section to bear such relation to analogous portions of a motion picture film of the same matter, that the synchronism of their effects will result when they are suitably advanced at a fixed ratio of speed, substantially as and for the purpose 95 described.

4. A modified copy of a phonographic record the phonic section of which is contracted at certain locations as compared with the original, whereby to cause the several portions of the copied phonic section to bear such relationship to analogous portions of a motion picture film of the same matter that synchronism of their effects will result when they are suitably advanced at a fixed ratio of speed, substantially as and for the purpose 100 described.

5. A modified copy of a phonographic record with certain portions of its phonic line omitted as compared with the original, whereby to synchronize it with a motion picture film.

6. A modified copy of a phonographic record with new portions interposed in its phonic line between other portions, as compared with the original, whereby to synchronize it with a motion picture film.

7. The process of making a modified copy of a phonographic record synchronous with a motion picture film which consists in altering, during the operation of copying, the locations of the sound producing portions of its phonic line, so that they bear the same proportionate relation to each other in the length of the line, as are borne to each other 120 125 130.

by the analogous optical effect producing portions of the motion picture film.

8. The process of making a modified copy of a phonographic record synchronous with a motion picture film which consists in omitting, during the operation of copying, from its phonic line such portions as will cause the remaining portions to be in the same proportionate relation to each other as are the analogous portions of the motion picture film.

9. The process of making a modified copy of a phonographic record synchronous with a motion picture film which consists in interposing, during the operation of copying, in its phonic line portions such as will cause the acoustical effect producing portions to be in the same proportionate relationship as are the analogous optical effect producing portions of the motion picture film.

10. The process of making a modified copy of a phonograph record synchronous with a motion picture film, which consists in omitting from and interposing in its phonic line, during the operation of copying, such portions as will cause its acoustical effect producing portions to be in the same proportionate relation to each other as are the analogous optical effect producing portions of the motion picture film.

11. The process of making a modified copy of a phonographic record synchronous with a motion picture film which consists in distributing, during the operation of copying, its acoustical effect producing portions along its phonic line in such manner as to bear to each other the same proportionate relationship as are borne to each other by the optical effect producing analogous portions of the motion picture film.

12. The process of making a modified copy of a phonographic record synchronous with a motion picture film which consists in extending the phonic line during the operation of copying at selected places for selected extents.

13. The process of making a modified copy of a phonographic record synchronous with a motion picture film which consists in contracting its phonic line at selected places for selected extents during the operation of copying.

14. The process of making a modified copy of a phonographic record synchronous with a motion picture film which consists in elongating certain portions of its phonic line and in shortening certain portions of its phonic line, to selected extents, during the operation of copying.

15. The process of making a modified copy

of a phonographic record synchronous with a motion picture film which consists in causing the modified copy to be moved at certain places to certain extents during the operation of copying, while the master record is at rest.

16. The process of making a modified copy of a phonographic record synchronous with a motion picture film which consists in causing the master record to be moved at certain places to certain extents during the operation of copying, while the modified copy is at rest.

17. The process of making a modified copy of a phonographic record synchronous with a motion picture film which consists in stopping the master record at certain points and advancing the modified copy independently to certain extents during the operation of copying.

18. The process of making a modified copy of a sound record to be synchronous with an analogous moving picture record which consists in relatively moving the master record and the copying surface during the act of copying.

19. The process of making a modified copy of a record synchronous with a motion picture film which consists, during the operation of copying, of stopping both the master and the modified copy and advancing either in either direction, to selected extents adapted to cause the sound producing portions of the modified copy to have the same proportionate relationship to each other as are had by the optical effect producing portions of the motion picture film.

20. The process of making a modified copy of a sound record synchronous with a motion picture film which consists in causing the modified copy to be advanced at a rate of speed during the operation of copying which varies at selected places for selected durations, as compared with the speed of the master.

21. The process of making a modified copy of a sound record synchronous with a motion picture film which consists in altering at selected places to selected degrees the angular attitude of the master record and the modified copy during the operation of copying, thereby to cause the acoustical effect producing portions of the modified copy to be in the same proportionate relation to each other as are the analogous optical effect producing portions of the motion picture film.
